J. O. TAYLOR,
OIL GAS BURNER,
APPLICATION FILED NOV. 29, 1918.

1,346,391.

Patented July 13, 1920.

Inventor

UNITED STATES PATENT OFFICE.

JAMES O. TAYLOR, OF PROVIDENCE, RHODE ISLAND.

OIL-GAS BURNER.

1,346,391.

Specification of Letters Patent. Patented July 13, 1920.

Application filed November 29, 1918. Serial No. 264,548.

To all whom it may concern:

Be it known that I, JAMES O. TAYLOR, a citizen of the United States, and resident of the city of Providence, in the county of Providence and State of Rhode Island, have invented certain new and useful Improvements in Oil-Gas Burners, of which the following is a specification.

This invention relates to combustion devices to be placed in a stove or like structure for the purpose of enabling the stove to use gasified liquid fuel, and the object of the invention is to improve the details of construction of such a burner and render the same more economical and effective.

With these and other objects in view, the invention consists of certain novel features of construction, as will be more fully described, and particularly pointed out in the appended claims.

In the accompanying drawings:

Figure 1— is a sectional side elevation showing the arrangement of my improved burner and illustrating the base thereof as mounted upon a stove grate, the rest of the stove not being shown.

Fig. 2— is a top view of the base member with the burner pipe and mixing chamber removed.

Fig. 3— is a detail in perspective showing the adjustable damper.

Fig. 4— is a top view showing the spirally corrugated walls of the cone-shaped mixing chamber.

Fig. 5— is a detail showing a portion of the mixing chamber with one of its bendable ears projecting from its lower edge.

Referring to the drawings, 10 designates the base of the burner, which is preferably formed hollow and elongated so as to fit into the fire box of a stove or the like and is designed more particularly to rest upon the grate 11, as illustrated in Fig. 1. This base member is provided with a top plate 12 through which two sets of draft openings 13 are shown, one at each end thereof to accommodate the device when two burners are mounted on this plate.

Around the edge of this plate is formed a rim or flange 14 and a pair of bosses 15 are formed at either end of this plate inside of the flange the same being internally tapped to receive the threaded ends of the burner-pipe standards 16.

These burner pipes are preferably formed substantially in the shape of the letter P,

one portion of each pipe being bent around in loop form and its free end 17 turned back to project toward the standard portion 16. This free end is plugged as at 18 and near 60 this end is formed an upwardly directed jet opening 19.

By my improved construction and arrangement of burner pipes, I am enabled to bend a stock pipe of iron or brass into exactly 65 the desired shape to form a complete burner pipe and that without producing joints or connections of any sort in the pipe, and by this construction it will be seen that I am enabled to screw the threaded end of each 70 pipe into its threaded boss without having one burner pipe in any way interfere with the positioning of the other.

Beneath the jet end of each pipe I have provided a shallow trough 20 which is filled 75 with asbestos wicking or the like, so that the oil may be run over from the jet if desired, to drop upon this wick, which, when lighted, then serves as a torch to light the jet end to assist in converting the oil supply into a 80 gas.

Over this lighting wick and about the openings 13 through the base plate, I have located a mixing chamber 21, the walls of which are preferably arranged in a conical 85 shape. The lower edge of this cone is provided with a plurality of downwardly extending ears 22 which are adapted to project through the openings 23 in the base and when bent to one side they serve to securely 90 lock this conical mixing chamber to the base.

In some instances it is found of advantage to form the walls of this mixing chamber with spiral corrugations 36 so that as 95 the air is drawn up through the openings 13 in the base these walls thus formed will impart to this column of air a spiral or whirling motion which will also act upon the rising jet of gas from the opening 19 thereby 100 serving to break up the flow of both and cause this gas to mix more thoroughly with the oxygen of the air, to produce a more perfect combustion and consequently a more intense heat with greater fuel economy. 105

In order to obtain a still greater efficiency from the flame I have also provided a spreader member 28 which is supported from the upper portion of the burner pipe by bands 29 and I have corrugated or formed teeth 30 about the edge of this spreader member so that the flame will be 110

broken up to permit the air to more readily mix therewith and so further intensify the heating efficiency of the burner.

The top of this spreader is preferably formed concave as at 31 for the purpose of receiving a supply of asbestos wicking which may be lighted in starting the stove to assist in heating and gasifying the oil supply as it is passing around to the jet 19.

10 In order to more perfectly control the air supply through the openings 13 I have provided a damper 24 which is centrally pivoted at 25 and is provided with an operating handle 26 extending up through the 15 segmental opening 27 in the base.

As a matter of convenience I have extended this heating wick 20 out beyond the edge of the mixing chamber so that it may be readily lighted from the outside without 20 removing the cone.

The supply to the burners is led from a receptacle (not shown) through the pipe 32 which is connected to the branch pipes 33 which lead up through the grate 11 and 25 short pipes 34 to the burner pipes 16. These branch pipes are each provided with a valve 35 so that either one or both of the burners may be lighted if desired. These branch pipes are preferably constructed of ductile 30 or bendable material such as copper, brass or the like whereby they may be bent to readily find their way through the stove grate and out through the draft openings in the front of the stove by which construction 35 my improved heater may be applied to any ordinary coal stove or furnace without being obligated to drill or bore holes or other-

wise disfigure the stove to which the device is applied.

I have shown and described this burner 40 as being double but a single burner pipe may be attached to a single base plate if desired.

The foregoing description is directed solely toward the construction illustrated, 45 but I desire it to be understood that I reserve the privilege of resorting to all the mechanical changes to which the device is susceptible, the invention being defined and limited only by the terms of the appended 50 claims.

I claim:

1. In an oil gas burner, a hollow base having a draft opening through its top plate, a substantially P-shaped burner pipe 55 secured to said top plate near one end thereof, a cone-shaped mixing chamber over said opening and into which the jet end of said pipe extends, and the walls of said chamber being spirally corrugated. 60

2. In an oil gas burner, a hollow base having a draft opening through its top plate, a substantially P-shaped burner pipe secured to said top plate near one end thereof, a cone-shaped mixing chamber 65 enclosing said opening and into which the jet end of said pipe extends, and bendable ears on said cone by which the cone is removably connected to said plate.

In testimony whereof I affix my signature 70 in presence of one witness.

JAMES O. TAYLOR.

Witness:

HOWARD E. BARLOW.
